ELECTRON DISCHARGE SYSTEM

Kenneth C. De Walt, Schenectady, N. Y., assignor
to General Electric Company, a corporation of
New York

Application May 17, 1930, Serial No. 453,392

6 Claims. (Cl. 250—36)

My invention relates to electron discharge systems and more particularly to certain improvements in systems employing electron discharge devices of the magnetic field divided or "split anode" type.

Electron discharge systems of the type to which my invention relates are shown and described in copending applications, Serial No. 397,893, filed October 7, 1929, by Norvel Douglas; Serial No. 10 320,709, filed November 20, 1928, Serial No. 389,067, filed August 28, 1929, by Elmer D. McArthur, and in my copending application Serial No. 398,249, filed October 8, 1929, and entitled "Electron discharge apparatus". My present application is a continuation in part of my above mentioned copending application.

My present invention has for its purpose to provide means whereby certain of the operating characteristics of systems of the type indicated may be improved and whereby, in general, the efficiency and practicability of these systems is increased.

The novel features which I believe to be characteristic of my invention are set forth with particularity in the appended claims. My invention itself, however, both as to its arrangement and method of operation together with further objects and advantages thereof may best be understood by reference to the following description 25 taken in connection with the accompanying drawing in which Fig. 1 represents an embodiment of my invention, and in which Figs. 2, 3 and 4 represent certain of the operating characteristics thereof.

Referring to the drawing, I have shown in Fig. 1 an electron discharge device of the split, or divided anode type. Connected between the anodes of the discharge device is an oscillatory circuit 2 in which oscillations are produced by action 30 of the discharge device. This circuit is coupled to a suitable load circuit 3 which, in the drawing, is represented as an antenna.

A cathode 4 extends longitudinally of the discharge device and between the two anodes. This 45 cathode is heated to incandescence by means of a source of electromotive force 5. A suitable electromotive force is impressed between the cathode 4 of the discharge device and the anodes thereof by means of a source 6 which is connected between the cathode and the midpoint 50 on the inductance of the oscillatory circuit 2. I have represented at 7 a suitable coil extending about the discharge device and which is energized from a source of uni-directional potential 55. Thus the coil produces a uni-directional mag-

netic field extending longitudinally of the discharge device and between the anodes thereof. As thus arranged the system comprises a now well known oscillation generator particularly adapted for the production of oscillations of short 60 wave length.

I have found that the efficiency and certain of the operating characteristics of apparatus of the type described may be very markedly improved by including in the circuit of the source of potential 6 a resistance which I have indicated at 9 in the drawing. This resistance may vary in value dependently upon the type of discharge device used, but I have found, in general, that the value of this resistance should be relatively high, and 70 such that the anode potential is given a poor regulation characteristic. That is, by reason of this resistance, the voltage applied to the anodes before current starts to flow and before oscillations start, is higher than the voltage applied to the 75 anodes during the flow of space current. For example in a particular case of a discharge device in which the cathode anode voltage was 1500 volts and which had a power rating of 25 watts the proper value of the resistance was in the 80 neighborhood of 5000 ohms. Through empirical methods I have found that the value of this resistance is approximately equal to the field intensity in gausses divided by the anode current expressed in amperes. 85

In Fig. 2 I have shown comparative characteristics of systems of the type indicated with and without the resistance 9 and from which certain of the advantages of my invention are apparent. Thus for example, in this figure the curve A represents the relation between the anode current and the intensity of the magnetic field between the anodes of the discharge device with the resistance 9 omitted from the circuit. It will be seen that as the field strength is increased from 90 zero, the plate current is at first diminished slightly and then rises somewhat abruptly to a relatively high value after which upon further increase of the field strength the plate current diminishes in accordance with the right-hand portion of the curve A until a point is reached at which the plate current suddenly drops to zero. 95

The curve B represents the same characteristic of the system in which a resistance of 5000 ohms is included in the anode circuit of the discharge device. It will be seen that in this system as the field strength is increased the plate current gradually diminishes in a definite predetermined relation until a certain field intensity is reached at which the plate current drops suddenly to zero. 100 105 110

Thus it will be seen that by use of the resistance in accordance with my invention, the abrupt peak in the anode current field intensity curve is eliminated, and thus excessive heating of the discharge device due to variations in the field strength is avoided.

The curve C of Fig. 2 represents the relation between the oscillatory current of the circuit 2 of the same discharge device when no resistance 10 is employed in the anode circuit. It will be seen that as the field strength is increased, oscillations start at about the point at which the anode current is maximum and increase rapidly and at a diminishing rate until a certain field intensity 15 is reached corresponding to the point 10 at which oscillations suddenly cease. If now the field strength be diminished, it will be found that oscillations will not again start until a point is reached indicated at 11 at which oscillations start with 20 full intensity; that is, with intensity indicated by the curve C at the field strength corresponding to the point 11. This indicates that for stable operation of the discharge device it is necessary to use a value of field intensity corresponding to 25 the point 11. This point is indicated by the point 12 upon the curve C. To obtain maximum efficiency computed as the relation between the output high frequency energy and the input energy of the discharge device, it is desirable to 30 operate the discharge device at approximately the maximum point of the curve C as indicated for example at the point 13. Thus there is a comparatively wide range of field intensity between the point of maximum efficiency and the 35 point where stable operation is procurable which can not be practically employed because of the unstable operation of the device.

The curve D represents the same characteristic of the discharge device employing 5000 ohms in the anode cathode circuit. It will be seen that 40 in general the curve is shifted somewhat to the left of the curve C. The point 13' represents that at which maximum efficiency of the discharge device may be had, and the point 12' that at which stable operation may be had. The range of field intensity variation over which unstable operation is had is thus materially decreased. Thus it is possible to use a field strength 45 which more closely approximates that at which maximum efficiency of the device is obtained and at the same time secure stable operation of the device. Thus the efficiency of the system is increased.

Referring to Fig. 3, I have shown further characteristics of discharge systems of the type indicated. In this figure curve E represents the relation between the anode current and anode voltage of an oscillation generator of the type indicated, over a certain range, whereas the curve 60 F indicates the relation between the oscillatory current in the oscillating circuit and the anode voltage.

Referring to the curves of this figure, it will be seen that if the anode current is adjusted at a 65 value corresponding to 14 on the curve E, the oscillatory current in the oscillating circuit will correspond to the point 14' on the curve F. If now the anode voltage be increased to a point 15 on the curve E, it will be seen that the plate current will be increased by an amount indicated as ΔI_b on the figure, whereas the change in high 70 frequency current in the oscillating circuit is indicated as ΔI_a on the drawing. Thus it will be seen that the anode current in the device is increased and hence there are greater losses in

the discharge device. At the same time the high frequency energy output from the discharge device is decreased at a materially more rapid rate than that of the increase in energy input of the discharge device. By including a resistance in 80 the anode circuit of the discharge device having the proper value, an increase in voltage of the source 6, or other cause tending to cause an increase in anode current, may be made to cause sufficient drop upon the resistance 9 to compensate for the voltage increase. Thus as the anode current increases the voltage between the anode and cathode may be maintained at a more nearly constant value and the current in the oscillating circuit will thus be less affected by the change. 85 In this way I have found that a very material increase in the efficiency of the device may be obtained by including this fairly large resistance in the anode circuit. These considerations point to a value of resistance which may be determined from the slope of the anode current anode voltage characteristic and which may be expressed as a constant multiplied by the slope of this characteristic. 90

In Fig. 4 I have shown an additional characteristic of my system indicating the relation between the efficiency of the system taking into consideration the energy dissipation in resistance 9 and the value of the resistance. It will be seen that as the resistance increases the efficiency is 100 at first diminished and then rapidly increases to a maximum value after which it again diminishes. Of course the proper value of resistance is that at about which maximum efficiency is obtained. 105

While in this description I have mentioned particular values of the resistance 9, it will of course be understood that I do not wish to be limited thereto since as is readily apparent from Fig. 4 of the drawing the value of this resistance 110 may vary over a fairly large range and still produce the advantages resulting from my invention.

What I claim as new and desire to secure by Letters Patent of the United States, is:

1. An oscillation generator comprising a discharge device having oppositely disposed anodes, a cathode arranged between said anodes, an oscillatory circuit connected between said anodes, a source of direct current potential connected between said anodes and cathode, means for producing a unidirectional magnetic field between said anodes having such value that oscillations are produced in said oscillatory circuit and means for eliminating rapid variations in current flowing between said cathode and anodes with respect to variations in field strength over a certain range thereof. 120

2. An oscillation generator comprising a discharge device having oppositely disposed anodes, a cathode arranged between said anodes, an oscillatory circuit connected between said anodes, a source of direct current potential connected between said anodes and cathode, means for producing a unidirectional magnetic field between said anodes having such value that oscillations 125 are produced in said oscillatory circuit and means for eliminating rapid variations in current flowing between said cathode and anodes with respect to variations in field strength over a certain range thereof. 130

3. An oscillation generator comprising a discharge device having oppositely disposed anodes, a cathode arranged between said anodes, an oscillatory circuit connected between said anodes, a source of direct current potential connected between said anodes and cathode, means for producing a unidirectional magnetic field between said anodes having such value that oscillations 140 are produced in said oscillatory circuit and means for eliminating rapid variations in current flowing between said cathode and anodes with respect to variations in field strength over a certain range thereof, said means comprising a resistance connected in circuit with said source of potential. 145

3. An electron discharge system comprising a discharge device having oppositely disposed anodes, a cathode arranged between said anodes, an oscillatory circuit connected between said 150

anodes, a source of potential connected between said cathode and said anodes, means for producing a unidirectional magnetic field between said anodes and a resistance connected in circuit with said source of potential, said resistance having a value determined by the slope of the curve expressing the relation between the current flowing between the cathode and anodes and the potential appearing between the cathode and

10 anodes.

4. An oscillation generator, comprising an electron discharge device having oppositely disposed anodes, a cathode located between said anodes, a source of potential connected between said cathode and said anodes, an oscillatory circuit connected between said anodes, means for producing a magnetic field between said anodes whereby oscillations are produced in said oscillatory circuit, said oscillations being unstable over 20 a certain range of variation in intensity of said magnetic field and means including a resistance in circuit with said source of potential for reducing the range of variations of said field strength over which unstable operation occurs.

5. An oscillation generator, comprising an electron discharge device having oppositely disposed anodes, a cathode arranged between said anodes, an oscillatory circuit comprising an inductance connected between said anodes, a source of potential connected between said cathode and said anodes, means for producing a magnetic field between said anodes of sufficient intensity to cause oscillations to be produced in said oscillatory circuit, and means whereby the potential applied to said anodes has poor regulation, said means comprising a high resistance connected in circuit with said source of potential.

6. An electron discharge device oscillator comprising an hermetically sealed container wherein are contained an electron emitting cathode, a plurality of anodes disposed thereabout, and means for subjecting the electrons flowing from said cathode to said anodes to a magnetic field, and, a source of potential having poor regulation connected to said anodes whereby the voltage applied to said anodes is higher prior to the time when oscillations start.
